UNITED STATES PATENT OFFICE.

EDWARD J. BUTTERFIELD, OF CHAMBERLAIN, SOUTH DAKOTA.

SHIPPING-RECEPTACLE.

1,157,206.

Specification of Letters Patent.

Patented Oct. 19, 1915.

Application filed March 13, 1913. Serial No. 754,044.

To all whom it may concern:

Be it known that I, EDWARD J. BUTTERFIELD, a citizen of the United States, residing at Chamberlain, in the county of Brule and State of South Dakota, have invented 5 certain new and useful Improvements in Shipping-Receptacles, of which the following is a specification.

This invention relates to improvements 10 in packing and shipping receptacles and more particularly to that class of packing and shipping receptacles known as barrels.

The primary object of this invention is 15 the provision of a sectional packing and shipping receptacle or barrel for use in the transportation of fruits, vegetables and their products, cement, flour, salt, and various other products of manufacture, to markets or consignees and one which may be easily 20 opened for access to its contents and the latter removed from either section thereof without disturbing the contents of the other section.

Another object of this invention is to construct 25 the sections of the improved barrel in such a manner that one section may be telescoped within another when they are emptied and thereby forming a compact and convenient form for returning to the original shipper, for reuse, or for transportation when empty and to provide one of these sections with means for preventing the spilling of the contents of the various sections when 30 they are made ready for shipping.

A still further object of this invention is 35 to construct a barrel of the class above set forth, made of sheet metal, thereby preventing the egress of moisture into the same besides insuring the safe transportation of the 40 products, relative to the breaking of the receptacle and against the loss of the products thereby occasioned.

With the foregoing and other objects in view, this invention consists in such novel 45 features of construction, combination and arrangement of parts as will be hereinafter more fully described, illustrated in the accompanying drawings and claimed.

In describing the invention in detail, reference 50 will be had to the accompanying drawings wherein like characters of reference designate like or corresponding parts throughout the several views and in which,

Figure 1 is a longitudinal sectional view 55 through the improved barrel; Fig. 2 is an enlarged detail view showing the manner of

connecting the two sections; and, Fig. 3 is a cross-sectional view taken on the line 3-3 of Fig. 1.

The improved shipping crate is preferably constructed of two sections 1 and 2, which sections are so shaped as to form half sections of a barrel commonly used in the transportation of various products. Each of the sections 1 and 2 have their smaller 60 ends closed by means of a head 3 or 4 and these heads are rigidly secured to the ends of the sections 1 and 2 by means of rivets or any suitable type of fastening means 5 and in such a manner as to form an air-tight 65 connection between the heads and the sides of the sections. The upper or large end of the section 2 has a hoop 6 securely mounted upon the outer surface thereof and passing annularly thereabout. The upper portion 70 of the hoop 6 projects above the edge of the side of the section 2 and has thumb screws 7 mounted therein at various intervals.

Secured to the inner surface of the large 75 end of the section 1 of the shipping crate is a member 8 which is preferably constructed of any desirable type of metal and is provided with an annular shoulder 9 which has the portion 10 extending downwardly therefrom. The member 8 is practically a hoop which engages the inner surface of the section 1 and the portion 10 thereof extends into the hollow portion of the section 2 of the shipping crate. Any suitable type of 80 fabric 11, such as burlap or the like is stretched across the opening in the portion 10 of the member 8 and the outer edge of the piece of fabric is folded upwardly so as to engage the outer surface of the portion 10 85 of the member 8 and is securely held thereupon by means of a metallic band 12. The side of the section 1 of the barrel is provided with a plurality of threaded apertures 90 therethrough which are arranged in such a manner as to receive the shanks of the thumb screws 7 for securely holding the sections 1 and 2 together after the same have been filled.

In the use of a shipping crate of this type 100 the fabric 11 is removed from off the portion 10 of the member 8 and the section is filled with the product which is to be shipped, the fabric is then stretched across the opening in the member 8 and the ring 12 forced 105 about the latter thereby holding the fabric in place and forming a closure, whereby 110

the contents of the section 1 will be prevented from spilling when the same is placed upon the section 2.

After the section 2 of the shipping crate has been filled with the product which is to be shipped, the section 1 is, by any suitable manner or means, placed upon the section 2 in a position as is clearly shown in Fig. 1 of the drawings or in such a manner that the enlarged ends of the two sections 1 and 2 will coincide and the hoop 6 will be disposed about the outer surface of the two sections at their point of connection. The thumb screws 7 are then screwed inwardly so that the shanks thereof will engage the threaded apertures in the section 1. This forms a means for holding the sections 1 and 2 together when they are to be shipped.

In practical fields certain minor features of construction, combination and arrangement of parts may necessitate alterations to which the patentee is entitled provided such alterations are comprehended within the scope of what is claimed.

What is claimed is:—

1. A shipping receptacle, including an upper and a lower section, a hoop mounted upon and carried by the said lower section

and passing annularly thereabout, said hoop having openings therein adjacent the upper marginal edge thereof, and thumb screws mounted in said openings for engagement with the said upper section, and a partitioning element carried by the upper section and disposed slightly below the upper marginal edge of the lower section, as and for the purpose set forth.

2. A shipping receptacle including an upper and a lower section, an annular flange secured to the inner surface of said upper section adjacent the lower end thereof, said flange having an annular shoulder and a portion extending downwardly from said shoulder and spaced from the lower marginal edge of the said upper section, and a ring engageable about said downwardly extending portion whereby to secure a fabric cover over said section, said fabric serving as a means to prevent the contents of said sections from mingling.

In testimony whereof I affix my signature in presence of two witnesses.

EDWARD J. BUTTERFIELD.
